UNITED STATES PATENT OFFICE.

MATTHEW C. SHARPNECK, OF CORNVILLE, ARIZONA, ASSIGNOR OF ONE-HALF TO E. BLOCK, OF PRESCOTT, ARIZONA.

SAFETY-RAZOR.

1,081,157.

Specification of Letters Patent.

Patented Dec. 9, 1913.

Application filed March 4, 1911. Serial No. 612,234.

To all whom it may concern:

Be it known that I, MATTHEW C. SHARPNECK, a citizen of the United States, residing at Cornville, in the county of Yavapai and State of Arizona, have invented new and useful Improvements in Safety-Razors, of which the following is a specification.

This invention relates to safety razors and it is the object of the invention to provide means whereby the blade of the razor may be simply and conveniently shifted laterally across the guard, whereby a shearing cut may be obtained.

Further objects of the invention will appear as the following specific description is read in connection with the accompanying drawing, which forms a part of this application, and in which:—

Figure 1 is a perspective view of the device. Fig. 2 is a side elevation with a portion of the casing removed. Fig. 3 is a detailed vertical sectional view. Fig. 4 is a top plan view with a part of the blade broken away. Fig. 5 is a perspective view of the blade used looking from the under side. Fig. 6 is a detail longitudinal section showing a modification of the driving mechanism.

Referring more particularly to the drawing, 1 represents a substantially semi-cylindrical casing to which is secured an operating or manipulating handle 2 preferably formed with a longitudinal channel 3 and which extends diagonally from the casing. Mounted within the casing is a frame 4 upon which is mounted a train of gears 5 including a spring drum 6 which drives the same. Included in the train is a suitable escapement mechanism 7 which controls the speed of movement and projecting from the bottom of the casing is the winding shaft of the spring drum by which the tension of the spring therein may be increased when desired. This winding shaft has secured thereon the usual turn button 8.

What will hereinafter be termed the secondary shaft of the train is indicated at 9 and is journaled in the frame 4 having its upper end projecting through the casing and provided with a wrist pin 10 carried upon the outer end of a crank arm 11. This wrist

pin is adapted to engage in a slot 12 formed in a substantially U-shaped shuttle 13 in which is detachably held the razor blade 14. This blade is mounted upon the top of the 55 casing and is adapted to reciprocate therover, being held in operative position by a strap 15 which lies over the blade adjacent the shuttle 13 and by removable cleats 16 which engage the rear edge of the shuttle 60 and hold the blade's cutting edge over the guard 17 which is formed from a continuation of the upper portion of the casing. The guard is slotted, as is usual in such constructions, for the passage of the beard.

In the modification shown in Fig. 6, the casing has mounted therein a small electric motor 18 which is connected to the secondary shaft 19 by means of a gear 20 and the current is led into the motor by the circuit wires 21 which pass through the handle 2. The casing in each form is provided with a door 22 by which the mechanism therein may be covered and so that access may be had thereto when repairs are needed or for any other suitable purpose. In the structure shown in Fig. 6 a suitable switch is preferably mounted upon the handle so as to control the current to the motor.

In the operation of the device the guard 80 and razor are pulled over the face at an acute angle thereto and with a straight pull, the motor being turned on so as to reciprocate the blade at the proper speed. This reciprocation of the blade across the teeth formed 85 by the slots in the guard acts in a similar manner to the ordinary cutter bar on a reaper or mowing machine and as the edge of the blade is straight a sawing action is produced which readily severs the whiskers from the face.

Having thus described the invention, what I claim as new is:—

In a safety razor, a casing, motor driven gear mechanism arranged therein, a guard 95 projecting outwardly from the casing, a strap formed from a narrow strip of uniform width throughout bridging the casing, a razor blade slidable on the guard and working within the strap, cleats detachably mounted in spaced relation to each other and also to the strap on the casing, and a sub-

stantially U-shaped shuttle detachably embracing one edge of the blade and reciprocatingly movable by the driven gearing and working against the strap and cleats respectively, the said cleats being arranged to sustain the shuttle in frictional engagement with one edge of the yoke.

In testimony whereof I affix my signature in presence of two witnesses.

MATTHEW C. SHARPNECK.
